UNITED STATES PATENT OFFICE.

FERDINAND W. KROGH, OF SAN FRANCISCO, CALIFORNIA.

TURBINE DEEP-WELL PUMP.

1,304,068.

Specification of Letters Patent. Patented May 20, 1919.

Application filed January 2, 1915. Serial No. 124.

To all whom it may concern:

Be it known that I, FERDINAND W. KROGH, of San Francisco, California, have invented certain new and useful Improvements in 5 Turbine Deep-Well Pumps, whereof the following is a specification.

My invention relates to pumps in general, but more particularly those of the turbine type, usually employed for pumping water 10 or other liquid in deep wells.

The objects of the invention are, first, to provide means for packing, holding and removing the pump casing from the well; second, to provide a sectional rotating shaft 15 for the impeller thereof and means for holding the sections together; third, to keep the shaft in perfect alinement within the well casing; fourth, to provide means for oiling the bearings of said shaft and to remove the 20 waste oil therefrom, and, fifth, means whereby the weight of the shaft is carried by the impeller when in operation; and, sixth, to use the well casing as a discharge pipe.

With these objects in view my invention 25 consists in the novel parts, combinations and arrangements set forth in the following specification, particularly pointed out in the claims at the end hereof, and illustrated in the accompanying two sheets of drawings, 30 forming a part of this application, in which—

Figure 1 is a vertical central section of the upper part of a well casing, also a section of the upper arrangement of my device, 35 particularly showing the sectional impeller shaft, one of its guide bearings and oiling device, also means for removing the waste oil and the pump casing.

Fig. 2 is a cross section taken on dotted 40 line *a*, *a* of Fig. 1, looking downward;

Fig. 3 is an enlarged detailed view of the pump shaft coupling.

Fig. 4 is a top view of Fig. 3.

Fig. 5 is a set screw to secure the coupling 45 of the pump shaft.

Fig. 6 is a vertical central section of the lower end of Fig. 1, showing the lower arrangement of my device and particularly a plurality of turbine pumps mounted in the 50 well casing and the method of holding, packing and removing said pumps; and

Fig. 7 is an enlarged section similar to

Fig. 6, but showing in section one of the pumps.

The same symbol of reference marks the 55 same part, in whichever view said part may appear.

In these figures: 1 represents the well casing which forms also the discharge of the pump, 2 the end thereof mounted upon the 60 upper part of the well and provided with outlet pipe, 3, secured to the end, 2, as at 4.

Within the well is the pump casing, 5, which may be arranged, if desired, in a plurality of sections, as shown in Fig. 6, and 6 65 is the impeller therein provided with the sectional driving shaft 7, secured at the upper end of the well by means of a central bearing, 8, and bracket, 9, which are mounted upon the discharge end of the well casing. 70

On the driving shaft is a collar, 10, which rests upon a bracket, 9, and supports the shaft thereon, when in an inoperative position and 11 is a pulley secured to the shaft by which the motive power is transmitted. 75

The sections of the driving shaft are united together by coupling, 12, which forms the holding means and is secured thereon by means of headless set screws, 13, having a square or other shaped aperture for driving 80 same in position, as shown in Figs. 3, 4 and 5.

Around the driving shaft is a sectional pipe, 14, the lower end of which is screwed, or otherwise removably secured, to the central portion of the pump casing, as at 15, as 85 shown in Figs. 6 and 7, and its upper end is secured to a downward cone-shaped projection, 16, of the bearing, 8, shown in Fig. 1, and forms the holding means for the pump 90 casing.

The number of sections of the pipe depend on the deepness of the well, or the length desired, and these sections are secured together by means of blocks, 17, and screw threaded 95 sleeves, 18, engaging the ends of the sections and the blocks and form at the same time guides for the driving shaft, 7, through which it passes, and means to keep the same in perfect alinement. 100

Within the lower section of pipe, 14, is packing, 19, which is pressed down upon the bushing, 20, of the pump casing 5, by means of a sliding tubular weight, 21, and com-

pression spring, 22, surrounding the driving shaft, 7, and located between the weight and block 17, of the lower section of pipe, 14. The object of this is to keep the waste oil, 5 from the bearing surfaces, from passing out through the pump and into the well.

The bearing surfaces of the blocks, 17, along the driving shaft, 7, are lubricated by means of oil pipe, 23, which is connected at 10 its upper end to the source of supply (not shown) and to the bearing block surfaces by means of T-shaped fittings, 24, and the waste oil therefrom passes out by pressure within the pipe, 14, through the channel, 25, in 15 the bearing blocks, 17, into the chamber, 26, formed in the downward cone-shaped projection, 16, and out through the outlet pipe, 27, secured to bearing, 8, and connected with the chamber, 26.

20 If desired, pipe 27, may be connected to suction means and therewith pump the waste oil out from the chamber, 26, and pipe, 14, and provided with stop-cock, 28, to regulate the passage within the pipe.

25 Upon the pump casing is a packing gasket, 29, provided with upturning annular edge fitting the well casing and forming thereby a packing joint at that point, the object of which is to prevent the water raised above 30 the pump from returning to the well casing below the pump.

The gasket, 29, is secured in position upon the pump casing by means of a flat ring, 30, held thereon by bolts, 31, secured to the casing, and coil springs, 32, around the bolts between the heads thereof and the ring 30, which press down the ring upon the gasket and facilitate the adjustment of the packing around the well casing while lowering 40 the pump.

If desired to remove the pump casing, the upturned annular edge of the gasket is released from engagement with the wall of the casing by means of wires or steel tape, 33, secured thereon at their bottom end, as shown in Figs. 6 and 7, while the upper ends are secured to the bearing, 8, and provided with knobs, 34, whereby the wires or tapes may be pulled up thereby disengaging the packing around the well casing, and the pump casing, 5, removed by pipe, 14, secured thereon.

In operation the rotary movement of the impeller creates a suction at the inlet, 35, and draws the impeller downward and as the water passes from the suction inlet into the passages of the impeller and the pump casing there will be pressure in the annular chamber, 36, between the impeller and the 55 casing, which will cause the impeller to move upward, and close the joint at 37 and when said joint opens by the downward movement of the impeller, create a suction from chamber, 38, through chamber, 39, and

passages, 40. This suction coacts with the 60 pressure in annular chamber, 36, to force the impeller upward again.

The upward movement closes the joint at 65 37 and cuts off the suction from chamber 38, which gradually acquires its normal pressure again by leakage through joints, 41.

The impeller oscillates between the two movements thus caused until it reaches an equilibrium. Thus the impeller, etc., are perfectly balanced.

Having thus described my invention, and an embodiment of it, in the full, clear and exact terms required by law, and knowing that it comprises novel, useful and valuable improvements in the art to which it pertains, 80 I here state that I do not wish to be limited to the precise construction and arrangement of the several parts, as herein set forth, as the same may be variously modified by a skilled mechanic without departing from the 85 spirit of the invention.

What I claim and desire to secure by Letters Patent of the United States is the following, to wit:

1. In combination with a deep well, a 90 pump casing therein, central suspending means for holding said pump casing within said well, packing detachably secured to said casing at the top thereof and engaging said well and means to disconnect said packing.

2. In combination with a deep well casing, a pump therein, suspending means for holding said pump within said well casing, a packing detachably secured to the pump casing at the top thereof and engaging said well casing, means to hold said packing in position upon said pump and well casing and means to disconnect the packing therefrom and to remove it from the well.

3. In combination with a deep well and a 105 pump therein suspended, means for holding said pump within said well, consisting of a sectional pipe secured centrally at one end to the pump casing and its opposite end to a central cone-shaped support fixed above said well, a packing detachably secured to said pump casing at the top thereof and engaging said well and means to disconnect said packing therefrom and to remove it from the well.

4. In combination with the shaft and the casing of a deep well pump, means for suspending said casing, said means being adapted to receive waste oil from the bearing faces of said shaft and means for removing said waste oil.

5. In combination with a well casing and a pump casing therein, a packing horizontally and detachably secured to the top of said pump casing and engaging the inner 125 wall of said well casing, whereby the portion of the casing above the packing may be used for a discharge of the water drawn by

the pump from the portion below the packing and pumped into it and means to disconnect said packing.

6. In combination with a well casing, and
5 a pump casing therein, a packing detach-
ably secured to said pump casing at the top
thereof and engaging said well casing and
means to disconnect said packing therefrom
and to remove it from the well.

In testimony that I claim the foregoing I 10
have hereto set my hand this 26th day of
December, 1914, in the presence of two wit-
nesses.

FERDINAND W. KROGH.
